UNITED STATES PATENT OFFICE.

JOHN A. WENTZ, OF PAOLA, KANSAS.

CORN-HUSKING IMPLEMENT.

SPECIFICATION forming part of Letters Patent No. 786,700, dated April 4, 1905.

Application filed February 26, 1904. Serial No. 195,450.

To all whom it may concern:

Be it known that I, JOHN A. WENTZ, a citizen of the United States, residing at Paola, in the county of Miami and State of Kansas, have invented certain new and useful Improvements in Corn-Husking Implements; and I do hereby declare the following to be a full, clear, and exact description of the invention, such as will enable others skilled in the art to which it appertains to make and use the same.

My invention relates to improvements in implements for husking corn, and is especially designed to provide an auxiliary means to the husking-hook now commonly used, so as to facilitate the husking operation.

To more fully describe the invention, reference is had to the accompanying drawings, illustrating the same, in which—

Figure 1 shows my invention applied to the hand of the operator; and Fig. 2 a plan view of the detached husking-plate, the dotted lines showing the position of the husking-hook proper before being bent to its operative position.

1 designates a hand-pad of leather or other suitable flexible material, which is so constructed as to be adapted to rest on the palm of the hand and the ball of the thumb, the inner end encircling the wrist and secured there-around by a strap 2 and buckle 3. The strap 4 is secured at one end to the forward upper corner of the pad 1 and is adapted to pass between the thumb and forefinger and attached to the rear upper portion of the pad 1 by the buckle 5 or in any other suitable way.

6 is a plate stamped from a suitable piece of metal and is adapted to be secured to the leather portion 1 in any suitable manner, 40 such, for instance, as by the rivets 7. This plate, as clearly shown, comprises the rear enlarged portion having the two forwardly-projecting tongues or blades 8 and 9, the tongue 8 being slightly longer than the tongue 9 and adapted to be bent inwardly over the base portion of the plate to form a husking-hook as ordinarily constructed. The tongue portion 9 is slightly bent to curve backwardly, as shown in Fig. 1, the under edge 10 forming

a cutting or gripping edge for the husks and 50 the upper edge 11 a support for the thumb.

It is well known that in shucking corn the inner husks oftentimes cling to the ear, and the peculiar shape of the husking-tongue 9 affords a ready means for separating this 55 clinging portion of the husks besides co-operating with the husking-hook proper to form a double shucker, the husking-hook 8 being adapted to strip off the husks in one direction of movement and the tongue 9 in the re- 60 verse direction.

Having thus described my invention, what I claim is—

1. A corn-husking implement comprising a base portion having a pair of normally forwardly-extending tongues stamped from a metallic plate, and forming a continuation of the peripheral edge thereof, the lower one of said tongues being slightly longer than the other and bent rearwardly over said base portion to form a husking-hook, and the other of said tongues being slightly curved backwardly to form an upper forwardly-extending auxiliary husking member, and means for securing said implement to the palm of 75 the hand.

2. A corn-husking implement formed from suitable metal, comprising an enlarged base portion provided with a pair of forwardly-extending tongues, the lower of said tongues being slightly longer than the other and bent rearwardly over said base portion to form a rearwardly and downwardly disposed husking-hook, and the upper member being bent backwardly to form an upwardly-disposed 80 curved auxiliary husking member, and means for securing said implement to the palm of 85 the hand of the operator.

3. In a corn-husking implement, the combination with a suitable flexible hand-pad, of 90 a metallic plate secured to said hand-pad, comprising an enlarged base portion, a husking-hook formed integral with said base portion, a husking-tongue formed integral with the peripheral edge of said base portion and 95 extending forwardly thereof, out of alignment with said husking-hook, and means for securing said pad to the palm of the hand,

with said husking-tongue extending forwardly below the thumb of the wearer.

4. In a corn-husking implement, the combination with a suitable flexible hand-pad and means for securing the same to the hand of the operator, of a metallic husking-plate secured thereto, comprising an enlarged base portion, provided with a pair of tongues normally extending forwardly of said plate and forming a continuation of the peripheral edge thereof, one of said tongues being slightly longer than the other and bent rearwardly

over said base portion to form a husking-hook and the other of said tongues being located at the upper corner of said plate and curved slightly backward to form an auxiliary husking member.

In testimony whereof I affix my signature in presence of two witnesses.

JOHN A. WENTZ.
